UNITED STATES PATENT OFFICE.

ROY D. CONWAY, OF CHATHAM, NEW JERSEY, ASSIGNOR TO WESTERN ELECTRIC COMPANY, INCORPORATED, OF NEW YORK, N. Y., A CORPORATION OF NEW YORK.

TESTING SYSTEM.

1,340,936.

Specification of Letters Patent.

Patented May 25, 1920.

Application filed May 9, 1918. Serial No. 233,460.

To all whom it may concern:

Be it known that I, Roy D. Conway, a citizen of the United States, residing at Chatham, in the county of Morris, State 5 of New Jersey, have invented certain new and useful Improvements in Testing Systems, of which the following is a full, clear, concise, and exact description.

This invention relates to testing systems 10 and more particularly to such systems which are especially applicable to testing marginal relays.

In certain telephone systems, particularly those in which both telegraph and telephone 15 circuits are combined, it is desirable to use for signaling purposes high frequency currents of approximately 133 cycles per second for the purpose of operating signals in connection with the telephone service, without 20 impairing the telegraph service. The ordinary type of signal used in connection with the telephone service being responsive only to a current of a very low frequency, such as 16 $\frac{2}{3}$ cycles per second, it is necessary to 25 provide means for translating the higher frequency current into the lower frequency current which is suitable for operating the signal. Marginal relays responsive only to 30 the currents of the higher frequency are frequently used for accomplishing this translation.

The object of this invention is to provide an improved system for testing the adjustment of such marginal type relays.

To attain this object, in accordance with 35 a feature of the invention, switching means is provided so that the alternating current relay to be tested may be operated as a buzzer from a source of direct current associated 40 with indicating means serving to indicate the sensitiveness of the adjustment of the contacts of the relay.

The nature of the invention will be more 45 clearly understood from the following specification and the annexed drawing in which the figure shows diagrammatically a relay to be tested and the apparatus for testing such relay in accordance with the present invention.

In the accompanying drawing, a marginal 50 relay 6, associated with the conductors 1 and 2 of an ordinary composited line through a retardation coil 3 and controlling a local circuit through its contact, is connected through normally closed contacts of

a jack 4. Only that portion of the composited line circuit which is essential to the proper understanding of the invention is shown and it may be further assumed that conductor 7 connects with the usual local 60 signaling circuit controlled by the contact of relay 6. A source of direct current 23 is adapted to be connected with jack 4 through a plug 5 and an indicating device 8. The contacts of jack 4 and plug 5 are so interconnected that the relay 6 operates as a buzzer when the source of direct current is connected to the jack 4. A double wound relay 9 is connected with jacks 16 and 17 which may be located as desired for convenience in testing the apparatus. Coöperating with jacks 16 and 17 and controlling the relay 9 is an indicating circuit connected with a plug 18 and including lamps 19 and 20. A relay 14 and a slow operating relay 75 13 associated with one contact of the indicating device 8 control the indicating lamp 20, while similar relays 11 and 10, respectively, associated with the other contact of the indicating device, control indicating lamp 19. Condensers 12 and 15 are connected in shunt 80 with the windings of relays 11 and 14, respectively, for the well known purpose of reducing the impedance of the circuits of such relays. In order to reduce the current transmitted through the contacts of the indicating device and the potential impressed upon the needle thereof, resistances 21 and 22 are included in the conductors connected with the needle. 85

It is thought that the invention will be more fully comprehended from the following description of the operation of the testing system. When it is desired to test the contact adjustment of marginal relay 6, the 95 plug 18 is inserted either in jack 17 or in jack 16. Assuming that jack 17 is employed, a circuit is thereupon established from battery 23 through the left-hand winding of relay 9, the contact of relay 10, the tip contacts of jack 17 and plug 18, lamp 19, and the sleeves of plug 18 and the jack 17 to ground. Relay 9 operates, completing a circuit from battery through the contact of relay 9, the winding of relay 10 and the contact of relay 11, to ground. A second circuit is completed from battery through the contact of relay 9, the winding of relay 13 and the contact of relay 14 to ground. A third circuit, also established, extends from 100 105 110

battery through the contact of relay 9, resistance 21, the needle of indicating device 8 and resistance 22, to ground. Relay 10 operates, removing the normal shunt circuit 5 existing around the right-hand winding of relay 9 and including such winding in series with the left-hand winding of relay 9 in a circuit established from battery through the windings of relay 9 in series, the tip contacts 10 of jack 17 and plug 18, lamp 19 and the sleeve contacts of plug 18 and jack 17, to ground. Due to the high resistance of the two windings of relay 9, lamp 19 does not light although relay 9 is maintained in an 15 operated position. Relay 13 also operates, thereby preventing the lighting of lamp 20. Plug 5 is then inserted in jack 4, opening the normally closed tip, ring and sleeve contacts thereof to disconnect the relay 6 from its 20 normal association with the retardation coil 3 and the local signaling circuit connected with the conductor 7. A circuit is thereupon established from battery through the contact of relay 9, indicating device 8, tip contacts of plug 5 and jack 4, both windings of 25 relay 6, ring contacts of jack 4 and plug 5, sleeve contacts of plug 5 and jack 4 and normally closed contact of relay 6, to ground. Current flowing over this circuit will cause 30 relay 6 to operate in the well known manner of a buzzer.

Due to the buzzerlike operation of relay 6, the current flowing through the indicating device 8 is periodically interrupted, thereby 35 causing the needle of such device to vibrate in synchronism with such interruptions. If the adjustment of the contacts of relay 6 is correct or within certain prescribed allowable limits to properly function upon the 40 predetermined operating current, the excursions of the needle will be such that although contact may be made with either contact of the device the pressure of such contact is such that the associated relays receive an 45 insufficient amount of current to cause their operation. As a result, lamps 19 and 20 will remain extinguished.

If, however, the contacts of relay 6 are 50 too tightly adjusted, the resistance of the circuit through the relay is reduced and a greater amount of current flows through the indicating device 8, thereby causing the needle to vibrate to and from the right-hand contact with an amplitude which is insufficient to permit the effective closure of the 55 left-hand contact. Upon the effective closure of the right-hand contact, a circuit is established from battery through the contact of relay 9, resistance 21, the needle and the 60 right-hand contact of the indicating device 8 and the winding of relay 11, to ground. Relay 11 thereupon operates, opening the circuit of and thereby releasing relay 10. By the closure of its contact, relay 10 reinstates 65 the normal shunt existing around the right-

hand high resistance winding of relay 9. The resistance of the circuit including lamp 19 is thereby sufficiently reduced to permit the lighting of such lamp to indicate that the contacts of relay 6 are too tightly adjusted. 70 When the needle of the indicating device swings away from the right-hand contact, relay 11 is released. Relay 10 is slow to operate so that although its operating circuit is re-established by the release of relay 11, it does 75 not become fully operated before the swinging needle of the indicating device returns to the right-hand contact, thereby reoperating relay 11 and consequently causing the release of relay 10. Therefore lamp 19 is main- 80 tained in a steadily lighted condition.

If the contacts of relay 6 are too loosely adjusted the resistance thereof is increased and less current flows through the winding of the relay and the indicating device so 85 that the needle vibrates to and from the left-hand contact with an amplitude which is insufficient to permit the effective closure of the right-hand contact. Upon the effective closure of the left-hand contact 90 a circuit is established from battery through the contact of relay 9, resistance 21, the needle and the left-hand contact of indicating device 8 and the winding of relay 14, to ground. Relay 14 operates, opening 95 the circuit of, and thereby releasing relay 13. By the closure of its contact, relay 13 causes the lighting of lamp 20 over a circuit established from battery through the contacts of relay 9 and of relay 13, the ring 100 contacts of jack 17 and plug 18, lamp 20 and the sleeve contacts of plug 18 and jack 17, to ground. The lighted condition of lamp 20 serves to automatically indicate that the contacts of relay 6 are too loosely ad- 105 justed to properly function under the service operating conditions. When the needle of the indicating device swings away from the left-hand contact, relay 14 is released. However, as in the former case, relay 13 is 110 slow to operate and serves to maintain the lamp 20 in a lighted condition, unaffected by the swinging of the needle of the indicating device.

In actual practice it may be found that a 115 convenient arrangement is to locate jack 17 at the jack panel on which jack 4 is located, while jack 16 may be placed near the marginal relays to be tested. After testing all of the marginal relays through jack 17 such relays as may be found to have 120 incorrect adjustments of their contacts may then be tested through the medium of jack 16. This jack being located near the relay being tested, the contacts of such relay may 125 be adjusted until neither lamp 19 nor lamp 20 is lighted.

While the invention has been disclosed as being embodied in the specific arrangement shown on the drawing, it is evident 130

that other forms may prove desirable under certain conditions.

What is claimed is:

1. In a testing system, in combination with a relay to be tested, a source of direct current, means adapted to serially connect the source of current with the winding and the contacts of the relay thereby causing the relay to periodically make and break its own circuit, and means to indicate the state of the adjustment of such contacts.
2. In a testing system, in combination with a relay to be tested adapted to vary its contacts upon a single strength of periodically varying current having a predetermined frequency, a source of direct current, means adapted to serially connect the source of current with the winding and the contacts of the relay thereby causing the relay to periodically make and break its own circuit, and means to indicate whether the relay contacts will function solely under the predetermined service conditions.
3. In a testing system, in combination with a relay to be tested, a source of direct current, means adapted to serially connect the source of current with the winding and the contacts of the relay thereby causing the relay to make and break its own circuit, and means to indicate variations in the contact pressure.
4. In a testing system, in combination with a relay to be tested having contacts adapted to function under predetermined service conditions when the normal contact pressure is intermediate two limiting values, a source of direct current, means adapted to serially connect a source of current with the winding and the contacts of the relay thereby causing the relay to make and break its own circuit and means to automatically indicate when the contact pressure corresponds with either limiting value.
5. In a testing system, in combination with a relay to be tested adapted to vary its contacts upon a single strength of a single predetermined frequency of periodically varying current, said contacts adjusted to be subject to a pressure intermediate two limiting values, a source of direct current, means adapted to serially connect a source of current with the winding and the contacts of the relay to cause the relay to make and break its own circuit, and means to automatically indicate when the contact pressure corresponds with either limiting value.
6. In a testing system, in combination with a relay to be tested, a normal operating circuit for the relay, contacts controlled by the relay and included in a local circuit, an indicating device, a source of current,

and switching means for disconnecting the relay from its normal operating circuit and the contacts thereof from the local circuit and to serially include said relay windings 65 and contacts in series with the indicating device and the source of current for determining the sensitiveness of the adjustment of the contacts thereof.

7. In a testing system, in combination 70 with a relay to be tested, a source of current, an indicating device, an indicating signal circuit, switching means for connecting the indicating device with the relay and the source of current, and additional switching 75 means for connecting the indicating circuit therewith.

8. In a testing system, in combination with a relay to be tested, an indicating device, a source of current, an indicating circuit including a plurality of signaling means, switching means for connecting the indicating device to the relay, additional switching means for connecting the indicating circuit with the indicating device, means 85 under the control of the last mentioned switching means for completing a circuit through the indicating device and the relay to be tested, and means under the control of the indicating device for automatically 90 closing a circuit through one of the signaling means of the indicating circuit.

9. In a system for testing relays, a circuit serially including the contacts and the windings of the relay to be tested, an indicating device, and means under the control of the indicating device for automatically indicating the adjustment of the contacts.

10. In a system for testing relays, a first circuit serially including the contacts and windings of the relay to be tested and the winding of an indicating device, a second circuit normally open including indicating means, and means under the control of the first mentioned circuit for closing the second 105 mentioned circuit.

11. In a system for testing relays, a first circuit serially including the contacts and the windings of the relay to be tested and the winding of an indicating device, a second circuit including signaling means and a variable resistance, a third circuit normally open and including signaling means, a fourth circuit under the control of the indicating device and including means to vary the resistance of the second circuit, and a fifth circuit under the control of the indicating device 110 and including means to close the third circuit.

In witness whereof I hereunto subscribe 120 my name this 3rd day of May, A. D. 1918.

ROY D. CONWAY.
